UNITED STATES PATENT OFFICE.

BENJAMIN PIERS, OF XENIA, OHIO.

LOCK.

SPECIFICATION forming part of Letters Patent No. 473,125, dated April 19, 1892.

Application filed September 28, 1891. Serial No. 407,045. (No model.)

To all whom it may concern:

Be it known that I, BENJAMIN PIERS, a citizen of the United States, residing at Xenia, in the county of Greene and State of Ohio, have 5 invented certain new and useful Improvements in Safety-Locks; and I do hereby declare the following to be a full, clear, and exact description of the invention, such as will enable others skilled in the art to which it 10 pertains to make and use the same.

My present invention relates to improvements in safety or burglar-proof locks; and the object of the invention is to provide a simple and inexpensive device of this character 15 by which the doors of dwelling-houses, &c., may be locked from the inside without the use of an ordinary key and secured in such manner that the door cannot be unlocked by any one upon the outside of the room or exterior 20 of the building when so secured, the device being at the same time adapted to be actuated under ordinary conditions from the outside for the purpose of locking or unlocking the door by the use of a key in the usual 25 way when the safety-button or device on the inside is in position to permit this to be done.

In using locks of the ordinary construction much trouble and inconvenience results from the loss or breakage of keys such as are generally 30 employed, and it therefore becomes necessary to provide duplicate keys. These, however, are liable to be mislaid when removed from the lock, and when left in the lock they punch holes in plastered walls and 35 catch onto clothing, &c., and great inconvenience is occasioned by the loss of a key when it is desired to hastily unlock a door. To overcome these and other objections to locks of the usual construction I have devised the 40 improved device hereinafter described, by which I dispense altogether with the use of a key for manipulating the lock from the inside of a room and at the same time adapt the lock to be operated by means of a key on the 45 outside, thereby avoiding the necessity of using indoor keys, and at the same time retaining all the advantages of a lock having a key for operating the same from the outside of the room or building.

50 My invention will first be described in connection with the accompanying drawings, and

then particularly defined in the claims at the end of this specification.

Referring to the drawings, in which like letters of reference are used to designate like parts of the device, Figure 1 is a sectional plan of my invention, showing the same applied to a door in the usual way. Fig. 2 is an elevation of the lock as it appears from the outside. Fig. 3 is a sectional bottom plan of Fig. 2. Fig. 4 is an elevation of the lock, partly in section, as it appears from the inside. Figs. 5 and 6 are detail views of the cap-piece of the knob, showing the pivoted pawl or cam-lever in different positions. Fig. 7 is a detail inside view of the catch with safety-button. Fig. 8 is a detail perspective view of the cap-piece with key operating upon the cam-lever, and Fig. 9 is a detail end view of the female portion of the knob.

A designates a bed-plate, which may be formed with the right-angled extension B, these parts being provided with suitable openings to receive the screws by which the bed-plate is secured to the door in the ordinary manner.

C designates an arbor or spindle, which passes through the bed-plate at right angles thereto and has secured to the inner end thereof a cross-handle or knob D, the handle being preferably attached by means of a screw-thread formed upon the spindle and engaging the interiorly-screw-threaded cylindrical shank of the handle. The arbor C has also secured thereto a swinging sliding locking plate or catch E, which carries at its free end a swiveled safety-button f, adapted to engage slots F' F² in the bed-plate, as hereinafter described.

G designates a hollow post or sleeve, which is fitted upon the arbor C, so as to rotate therewith and at the same time permit the arbor to slide back and forth therein. This connection is made by slotting the post longitudinally, as at g, to receive the ends of a pin c, which passes transversely through the arbor and also through a sliding thimble or sleeve H, which is fitted to rotate and slide back and forth upon said post, the arbor and sleeve being thus adapted to be rotated and slid back and forth together as one.

The inner end of the post G projects through

the bed-plate A, and has rigidly secured thereto a swinging guide-plate E', which is provided with an elongated slot to receive the safety-button f of the swinging catch E and hold the same in proper position to engage either one of the slots F' F² when the knob is turned in the desired direction.

I designates a coiled or other suitable spring, which is placed upon the post G between the enlarged end of the thimble H and the bed-plate A and tends to force said thimble outward, together with the arbor and the catch E, attached thereto, so as to hold the catch normally in engagement with one of the slots F' and F² with the door locked or unlocked, as may be desired.

J designates a sliding spring-pressed latch, which may be of any desired construction, but which is preferably formed integrally with or attached to a sliding yoke or frame K, which is placed astride the arbor G and is provided with elongated slots k (shown in dotted lines in Fig. 2) to receive lugs or pins k', which project from the bed-plate into said slots, these parts serving to guide the frame K as it moves back and forth for the purpose of engaging or disengaging the latch with the keeper L. A spring l may be attached to the extension B of the bed-plate or other suitable part of the device, so as to hold the latch J normally in engagement with the keeper.

The frame K has secured thereto a thumb-piece k², which projects through a slot k³ in the bed-plate in position to be pressed by the thumb or finger for the purpose of sliding the frame backward against the pressure of the spring l when it is desired to disengage the latch. The frame K is also provided with a projecting lug or two-faced cam-piece M, for a purpose to be described. A cylindrical shell or barrel, which may have formed therewith or secured thereto the recessed head or female portion N' of the knob N, is journaled upon the thimble H, so as to rotate freely thereon.

N² designates a cap-piece, which forms the male portion of the knob and which is recessed interiorly and provided with a spring-pressed pawl or pivoted cam-lever n, the cam portion n' of which is held normally by spring-pressure against a pin n², which projects from the inner face of the cap-piece adjacent to the key-hole O. A second pin o projects from the cap-piece in such position as to engage an open-ended slot in the shank of the key S, so as to permit the key to be rotated for the purpose of actuating the cam lever or pawl n, and a third pin o', also projecting from the inner face of the cap-piece, is adapted to arrest the movement of the key when the latter has been turned far enough to throw the cam piece or pawl into the path or track of the cam-faced end h' of the extension h of the thimble H, in which position of the cam-lever the cam-face h' will impinge against the cam portion n' of the lever when the knob N is rotated and force the thimble

H and the arbor C inward against the pressure of the spring I, so as to disengage the catch E. The interiorly-recessed head N' is formed with a depression or countersink N³ to receive the cam portion n' of the cam-lever n when the lever is thrown back out of the path of the cam-faced end h' of the thimble. Adjacent to said countersink is formed a circular recess or depression to receive the end of the key S, when the latter is inserted in the key-hole of the knob and serve as a bearing therefor when the key is turned to actuate the cam-lever.

The cap-piece N² has an opening q through the same to receive a set-screw q', as shown in dotted lines in Fig. 3, which screw is adapted to be screwed into the interiorly-screw-threaded outer end of the post G, with its head resting upon shoulders formed by the reduced portion of the opening q, so as to secure the parts of the knob and the thimble in position upon the post and at the same time permit the knob to be rotated for the purpose of locking or unlocking the door.

The head N' may, if desired, be secured to the cap-piece N² by additional screw-bolts; but for ordinary purposes the set-nut q' provides a sufficient fastening for these parts. In order to prevent tampering with the lock and derangement thereof, the set-screw q' is housed in the opening or countersink q of the cap-piece, and is concealed from view by means of a removable plug q³, as shown in Figs. 2 and 3.

To limit the movements of the catch E, so as to cause the same to stop in position for the button f to engage the slots F' F², the shank of the swinging guide-plate E' is provided with a curved slot e, which is engaged by a pin e', projecting from the face of the bed-plate A, as shown in Fig. 4, this slot and pin forming a secret stop, which is concealed by the catch E.

In order to prevent the door from being unlocked from the outside, the handle F may be given a quarter-turn, which will turn the button f athwart the opening F' in the bed-plate, and in this position of the button it cannot be withdrawn and the latch J will be retained in the keeper and securely held in position with the door locked. The device is thus adapted to serve as a burglar-proof lock, the button being inaccessible to any person on the outside and it being impossible to actuate the latch until such button is released.

The operation of my invention is as follows: The door being supposed to be locked, the button f of the latch may be disengaged by drawing upon the knob or handle D from the inside so as to separate the parts E E', as indicated in Fig. 1, in which position the catch E and guide-plate E' may be given a quarter-turn, so as to bring the button into alignment with the slot F², as indicated in Fig. 4, in which position of the parts the latch J on the inside may be slid back and forth by pressure upon the thumb-piece k² in the usual manner, and

the knob N on the outside, which is normally loose upon the arbor or thimble, may also be rotated, so as to cause the cam or projection N⁴, secured to the cylindrical shank or barrel of the knob, to engage the lug or cam-piece M upon the frame K and move the latch J backward, so as to disengage the same from the keeper L. When, however, the button 7 is in the slot F', it serves as a stop to prevent the frame K from being slid back, and it is necessary to turn the catch so that the button may engage the slot F² before the latch can be disengaged from the keeper. This may be done from the inside by drawing upon the knob D, as stated, and when the lock is in the last-mentioned position (shown in Fig. 4) the latch J may be slid back at pleasure from either the outside or the inside of the room; but in the former position, with the button 20 in the slot F', the latch cannot be disengaged from the keeper. To unlock the door from the outside, the key S will be inserted in the opening O of the cap-piece N² until the end thereof rests in a recess or countersink in the portion N' of the knob, as shown in Fig. 3, whereupon the key may be rotated so as to cause the flange thereof to engage the cam-lever n and force the cam portion n' thereof into the depressed or lowermost portion of 25 the cam-faced end h' of the thimble H, as indicated in Fig. 3, in which position by turning the knob N the cam-piece n' will ride upon the cam-face h' and force the thimble outward, together with the arbor C and swinging catch E, to the position shown in Fig. 1, and thereupon the further rotation of the knob will move the catch E a quarter-turn, so as to permit the button to be forced by the spring I into the slot F², and then on releasing the cam-lever the knob may be rotated without 30 affecting the catch, for the purpose of disengaging the latch J, as above described.

The door may of course be locked from the outside by manipulating the key and knob, as described, and turning the catch E in the reverse direction.

It will of course be understood that the construction and arrangement of parts hereinbefore described may be modified in a number 45 of ways without departing from the spirit of my invention, and hence I do not desire to be limited to the exact construction described and shown.

If desired, the swinging catch may be actuated from the outside by dispensing with the use of a key and attaching a rotatable knob adapted to be locked to the arbor and forced inward therewith against the pressure of the spring in a manner similar to that described 55 and shown in an application filed simultaneously herewith, Serial No. 407,046, in which I have described and shown a lock for closets, cupboards, &c., comprising a sliding spring-pressed catch, secured to an arbor or spindle, which is provided at one end with a rigid operating-handle and at the other end with an operating-knob, which is normally loose

upon the spindle, but adapted to be locked thereto, so as to move the same inward and force the catch out of engagement with the keeper or locking-plate. I do not, however, desire to claim in this application any matter covered by the claims of said concurrent application, and I disclaim herein the subject-matter covered by the claims of said case. 75

Having thus described my invention, what I claim as new, and desire to secure by Letters Patent, is—

1. A safety-lock comprising the bed-plate, the latch, the hollow post, the sliding arbor 80 rotatably secured within said post, the spring-pressed catch secured to said arbor, the sliding thimble fixed to said arbor so as to rotate therewith, the knob adapted to rotate freely on said thimble, and means for forcing the 85 thimble and catch inwardly against the spring-pressure so as to disengage the latch, substantially as described.

2. In combination with the bed-plate, the spring-pressed latch, means for actuating said 90 latch, the swinging spring-pressed catch, the arbor to which said catch is secured rotatably mounted on said bed-plate and provided at one end thereof with a rigid cross handle or knob and at the other end with a loose rotat- 95 ing knob, and means for engaging the knob so as to force the arbor inward against the pressure of the spring and disengage the catch, substantially as described.

3. In combination with the bed-plate, the 100 latch, the keeper, the swinging spring-pressed catch, means for operating said catch, and a safety-button whereby the catch may be secured so as to bind the operating mechanism thereof and the latch in immovable positions, 105 substantially as described.

4. In combination with the bed-plate, the latch, the keeper, the swinging spring-pressed safety-catch, the arbor to which said catch is secured, the hollow post, the thimble having 110 the cam-faced extension connected to said arbor so as to rotate therewith, the knob rotatably secured on said thimble, and the cam-lever adapted to engage said thimble and thereby disengage the catch, substantially as de- 115 scribed.

5. In combination with the bed-plate, the latch, the swinging spring-pressed catch, the arbor which supports said catch, the sleeve or thimble fixed to said arbor and having the 120 cam-shaped end or extension, the knob rotatably secured on said thimble and the cam-lever secured to said knob, and means for engaging said cam-lever and thimble and thereby disengaging the catch, substantially as de- 125 scribed.

6. In combination with the bed-plate, the sliding spring-pressed yoke or frame having the thumb-piece or handle and the latch rigid therewith, the cam-faced projection or lug 130 rigidly secured to said yoke, the rotary knob provided with a cam adapted to engage said lug, and the pins on said bed-plate adapted to engage slots in said yoke so as to guide the

yoke in its movements back and forth, substantially as described.

7. In combination with the bed-plate, the keeper, the latch, the sliding frame which supports said latch, the thumb-piece or handle on said frame, the sliding arbor rotatably mounted on said bed-plate and provided at one end with a rigid operating-handle and at the other end with a rotary knob adapted to 10 actuate the latch, and means, substantially as described, whereby said knob is adapted to actuate the arbor and disengage the catch, substantially as described.

8. In combination with the bed-plate, the 15 latch, the swinging spring-pressed catch, the arbor which supports said catch, the hollow post, the thimble or sleeve on said post, the rotary knob journaled on said thimble, the latch-actuating cam on said knob, the cam-shaped extension rigid with said thimble, the 20 spring-pressed cam-lever secured to said knob, and the key whereby said cam-lever is adapted to be thrown into the path of said cam-shaped extension so as to actuate the thimble 25 and arbor and thereby disengage the catch, substantially as described.

9. In combination with the bed-plate having the vertically and longitudinally elongated slots therein, the swinging catch, the arbor 30 to which said catch is secured, and the spring which is adapted to hold the catch normally in engagement with one of said slots, substantially as described.

10. In combination with the bed-plate having the catch-receiving slots therein, the sliding spring-pressed latch, the sliding spring-pressed arbor rotatably mounted on said bed-plate, the swinging plate secured to said arbor, and the swiveled safety catch or button carried 35 by said swinging plate and adapted to engage said slots so as to hold the parts locked or unlocked, substantially as described.

11. In combination with the bed-plate having catch-receiving slots therein, the arbor 40 mounted on said bed-plate, provided with an inner rigid operating-handle and an outer rotary knob normally free to rotate thereon, the swinging spring-pressed catch secured to

50 said arbor and movable therewith, the spring-pressed latch, the thimble, the swinging guide-plate, and means whereby the catch may be operated from the outside by the rotation of the knob, substantially as described.

12. In combination with the bed-plate, the latch, the swinging catch, the arbor which 55 carries said catch, the thimble locked to said arbor so as to move therewith, the knob adapted to rotate freely on said thimble and provided with a cam for actuating the latch, the operating-handle rigidly secured to said arbor, 60 the cam-shaped extension or screw rigid upon said thimble, the cam-lever for engaging said cam-shaped extension, and the key for actuating said cam-lever, substantially as described.

13. A burglar-proof lock comprising the bed-plate, the keeper, the spring-pressed latch, means for operating said latch, the swinging 70 spring-actuated catch provided with a safety-button, the arbor which supports said catch 75 rotatably mounted on said bed-plate, the hollow post, the thimble on said post, the knob rotatably secured on said thimble, the cross handle or knob rigidly secured to said arbor, the cap-piece, the cam-lever housed in said 75 cap-piece, and the key for actuating said cam-lever, substantially as described.

14. In combination with the bed-plate, the sliding spring-pressed frame having the latch, the operating thumb piece or handle, and the 80 cam-faced lug or projection rigid therewith, together with the rotary knob provided with a cam adapted to engage the lug on said frame so as to disengage the latch, substantially as described.

15. In combination with the sliding arbor and swinging spring-pressed catch supported thereby, the swinging guide-plate and the stop for limiting the movements of said plate, substantially as described.

In testimony whereof I affix my signature in presence of two witnesses.

BENJAMIN PIERS.
